EDWARD CRAIG, OF ST. JOSEPH, MICHIGAN, ASSIGNEE TO SARANAC MACHINE COMPANY, OF ST. JOSEPH, MICHIGAN, A CORPORATION OF MICHIGAN.

INSIDE BOX-END-STAPLING MACHINE.

1,186,285.

Specification of Letters Patent. Patented June 6, 1916.

Application filed July 18, 1911. Serial No. 639,144.

To all whom it may concern:

Be it known that I, EDWARD CRAIG, a citizen of the United States of America, and resident of St. Joseph, Berrien county, Michigan, have invented a certain new and useful Improvement in Inside Box-End-Stapling Machines, of which the following is a specification.

My invention relates to stapling machinery for securing the end walls of wire bound boxes or crates in place. Machines of this kind are, in a general way, divided into two classes, first, those that drive the staples from the outside of the box, so that they pass through the reinforcing cleats and then into the said end walls; second, those which drive the staples from the inside of the box, so that the staples pass through the end walls and then into the cleats.

My invention relates to stapling machines of the second class, which are commonly known as "inside staplers," being adapted to perform the stapling operation inside of the box.

The object of my invention is to provide an inside box end stapling machine in which the staple is made and driven by practically one and the same mechanism, without changing the direction of the staple, whereby one mechanism for making the staple and another distinct and separate mechanism for driving the staple are not necessary, the insertion of the staple, with my improved construction, being accomplished by practically a continuation of the mechanical action or operation by which it is made, as distinguished from other inside box end staplers, heretofore employed for this purpose, in which the staples were made at one point and then fed in a long row to another point where they were driven, or in which the staple was made by movement at one angle and then shifted some distance and then inserted at another angle, which like other methods of a more or less similar nature, involved the use of a more or less complicated and unsatisfactory construction.

To the foregoing and other useful ends, my invention consists in matters hereinafter set forth and claimed.

In the accompanying drawings Figure 1 is a side elevation of an inside box end stapling machine involving the principles of

my invention, showing the stapling mechanism thereof in vertical section. Fig. 2 is a plan view of the outer end portion of the arm or support upon which the head of the box rests while being stapled, and in which the stapling mechanism is contained. Fig. 3 is an enlarged side elevation of the stapling mechanism shown in Fig. 1. Fig. 4 is a view looking at right-angles to the upper inclined edge of the mechanism shown in Fig. 3. Fig. 5 is a perspective of the staple former. Fig. 6 is a perspective of the loop bar upon which the staple is bent by the said staple former. Fig. 7 is a longitudinal section of the stapling mechanism on line 7—7 in Fig. 3. Fig. 8 is a perspective of the staple driver. Fig. 9 is a perspective of the staple carrier. Fig. 10 is a cross-section of the stapling mechanism on line 10—10 in Fig. 7, showing the box or casing in which the same is inclosed. Fig. 11 is a detail sectional view of one corner of the crate or box, showing the manner in which the staples are inserted.

As thus illustrated, my invention comprises an upright support or body A, of any suitable character, upon which the casting B is mounted. This casting has a horizontally extending portion b that serves as an arm or support for the head of the box or crate, and a shorter upper arm b' which serves as a bearing for the pivoted lever C, which latter is provided with an adjustable foot c which bears upon the box or crate to resist the upward thrust of the stapling mechanism. This lever C is operated by a rotary cam D of such character that the foot c moves up and down and automatically clamps the box or crate in place at the proper time. The stapling mechanism E is located in the hollow outer end portion b² of the arm b, and is disposed at an angle, in the manner shown, whereby the staples are inserted obliquely, as shown in Fig. 11. For this purpose the outer end of the arm b is provided with a slot b³ through which the staples are inserted upwardly in such manner that they incline outwardly, each staple passing into the cleat near one corner and in a direction extending toward the other corner. In other words, the staples are not driven straight into the cleat, as was heretofore the practice, but are driven at an angle,

whereby the staples are less liable to pull out and the box is rendered stronger.

The construction and mode of operation of the stapling mechanism E are as follows:

- 5 The staple driver e, shown in Fig. 8, is in the form of a bar having one end thereof provided with a portion e' which drives the staple. This bar, which is called the staple driver, is also provided with a longitudinal 70 groove or recess e², and with a couple of pins or studs e³, an end plate e⁴ being secured to said bar and provided with a small opening e⁵ which communicates with the end of the said groove or recess. Rack teeth e⁶ are 75 provided along one edge of the said driver e, in the manner shown. The staple carrier F, shown in Fig. 9, is in the form of a flat steel bar provided at its forward or upper end with bevels f and f', formed by cutting off 80 the corners of the bar, the bevel f being adapted to engage the under surface of the end wall of said box or crate, the said staple carrier being thus adapted to project into the corner of the said box or crate, whereby 85 the staples are brought into proper position for driving. The said staple carrier F has a longitudinal slot f² for the staple, the two prongs thus formed being provided on their inner opposing surfaces with longitudinal 90 grooves f³ that serve as guides for the staples. The other end of the said staple carrier is provided with a wider but shorter slot f⁴, and with a small opening f⁵ near the inner end of said slot. A rod f⁶ has a bent 95 end portion that engages the opening f⁵, and the other end of said rod slides in the opening e⁵, a spring f⁷ being mounted on the said rod and arranged for compression between the plate e⁴ and the bent end portion of said 100 rod. A latch G is pivoted on one of the pins or studs e³, as shown in dotted lines in Fig. 3, and is provided with an end portion g adapted to engage the corner f⁸ of the staple carrier, whereby the staple driver and the 105 said staple carrier are locked together and must move in unison for a portion of the upward stroke of the stapling mechanism. A plate g' is interposed between the staple driver and the staple carrier and the inner 110 surface of the box or housing b² in which the stapling mechanism is inclosed. The lower beveled end portion g² of the said plate g' serves as a cam for engaging the rounded shoulder g³ on the latch G, where- 115 by the portion g is disengaged from the corner f⁸ of the staple carrier as soon as the latter reaches the end of its stroke, and as soon as the beveled end of the staple carrier engages the inner corner of the box. 120 The staple former H is of the usual form, being provided with a longitudinal slot h for the staple, the two prongs thus formed being provided on their inner opposing parallel 125 surfaces with grooves h' which serve as guides for the staple, and the ends of said

prongs being notched or grooved at h² to engage and cut off the wire in the usual and well-known manner, the length of the staple depending, to a certain extent, upon the width of the staple former—that is to say, 70 the length of the piece of wire which is cut off depends upon the width of the staple former. In this case a comparatively long staple is necessary, and hence a comparatively wide staple former is necessary. This 75 staple former, however, is rigidly connected with the staple driver, which is not usually the case, as in the ordinary stapling mechanism of this general character the staple former and staple driver are connected together in a manner similar to the way in which the staple carrier F and the staple driver e are herein described and shown connected together. The said staple former H is provided with a couple of openings h³ 80 that receive the pins or studs e³, whereby the staple driver and the staple former have the same length of stroke, the two being separated, however, by the thickness of the staple carrier F, which latter is interposed flatwise between them. The loop bar I, shown in Fig. 6, has a shank or stem i by which it is adjustably mounted in the end of the loop bar holder i' and held therein by a set screw i². This loop bar has a portion 85 i³ which serves as the anvil upon which the wire is bent to form the staple. Said loop bar is also formed with an overhanging portion i⁴, the slot i⁵ between this portion and the portion i³ terminating in the side of a 90 round hole or opening i⁶ which receives the wire. The loop bar holder i' is pivoted at i' upon the box or housing for the stapling mechanism, and is provided with a portion 95 i⁷ which has a straight edge that bears 100 against the flat face or outer surface of the staple former. A spring i⁸ connects the shorter end portion i¹⁰ of the said loop bar holder with some portion of the interior of the arm b, said spring serving by its tension 105 to, at the proper time, pull the loop bar holder into such a position that the portions i³ and i⁴ of the loop bar will enter the slot f² of the staple carrier. As shown in Fig. 4, 110 the loop bar is in position to have the wire 115 enter the opening i⁶ through a tube J, and when the stapling mechanism moves forward the length of wire is cut off by one forward corner of the staple former and then bent 120 by the latter to form the staple. Then as 125 the mechanism moves backward the loop bar moves over in front of the ends of the staple driver and carrier, by reason of the action of the spring i⁸, and as the forward motion continues the previously made staple is engaged by the grooves f³ and held therein, and as the driver moves along, the end of the portion e' thereof strikes the rounded or beveled surface of the portion i⁴ and thereby crowds the loop bar out of the path of the 130

staple driver and into the path of the staple former, whereby another staple is made at the same time that the previously made staple is driven. In other words, the staple former and loop bar are coöperating to make one staple at the same time that another staple is being driven by the coöperation of the staple carrier and driver.

The stapling mechanism is operated by a segmental pinion K which engages the rack teeth e^6 on the staple driver. This pinion is suitably mounted on the arm b , and is operated by a pitman k , which latter is in turn operated in a reciprocating manner by the eccentric cam and strap k^7 on the shaft L , which latter is mounted in suitable bearings on the casting B , or in any other suitable manner. By this arrangement the pinion K is oscillated to reciprocate the stapling mechanism. The wire for the staples is fed by feed rolls M which are operated by a ratchet mechanism m , said mechanism being in turn operated by a pitman m' , and the said pitman being operated by an eccentric cam and strap m^2 on the aforesaid shaft. It will be understood that these cams are so relatively adjusted that the wire is fed at the proper time, and that the stapling mechanism is actuated in the proper manner.

With further reference to the arm b , it will be seen that the end thereof is provided at one side with a long bevel b^4 , and at the other side with a short bevel b^5 , which bevels facilitate the manipulation of the box or crate on the machine, to permit the staples to be inserted obliquely to the length of the cleats, so that each staple is inserted crosswise of the grain of the wood of the veneer, to a certain extent, which is desirable in order that the head of the staple may securely fasten the veneer to the cleat. With this construction, and as the staple carrier F does not form the staple, it is possible for the driving mechanism to operate close to the vertical side wall of the box, and to insert the staple obliquely or at an angle, which would not be the case if the said carrier was also a staple former, as in that case the corners thereof could not be cut off, as these corners would be necessary for determining the length of the wire from which the staple was made. The staple former H is not required to move into engagement with the corner of the box or crate, nor is it required, with this mode of operation, to operate very close to the box or crate; and consequently it can be made of any desired width and may be provided with the usual square ends for cutting off and bending the wire. The staple carrier picks up the staple and moves forward until it brings the staple into position for driving, and the staple driver is then unlocked from the staple carrier, in the manner previously described, and the staple is then driven. At the same time, the staple

former and loop bar are coöperating in making another staple. The staples are driven in exactly the same direction that they are formed—that is to say, they are driven at the same angle at which they are formed or made, and the forming and driving operations are so close together that the two operations are practically performed by one and the same mechanism, like the ordinary stapler, notwithstanding that with my improved construction the staple is not driven by the same forward stroke by which it is made. In this way, an inside box end stapling machine is provided in which the stapling mechanism is comparatively simple and of such character that the staples are practically made at the point where they are driven.

With further respect to the insertion of the staples, it will be seen that each staple is held on the loop bar by the portion l^1 and the opening l^2 , while the staple former is being retracted. It will also be seen that during the insertion of the staples the outer end portion of the support b engages the side walls of the box or crate to gage the position of the staples.

I do not limit myself to the exact construction shown and described.

What I claim as my invention is:—

1. In a stapling machine, a staple former and a staple driver which are rigidly connected together to move always in unison, and a movable loop bar coöperating with said staple former to form the staple. 100
2. In a stapling machine, a staple carrier provided with a guide slot for the staple, said carrier disposed at a fixed angle, a staple driver provided with a portion which operates in said slot to insert the staple, a yielding connection between said staple carrier and driver, a lock between the staple carrier and driver, means for unlocking the driver as soon as the staple carrier brings the staple into position for driving, and mechanism for making and delivering staples to said staple carrier. 110
3. In a stapling machine, a staple carrier provided with a slot for the staple, a staple driver provided with a portion which operates in said slot to insert the staple, a yielding connection between said staple carrier and driver, a lock between the staple carrier and driver, means for unlocking the driver as soon as the staple carrier brings the staple into position for driving, mechanism for making and delivering staples to said staple carrier, said mechanism comprising a staple former and loop bar, and means whereby the said loop bar is moved into the path of the staple carrier. 120
4. In a stapling machine, a staple carrier provided with a slot for the staple, a staple driver provided with a portion which operates in said slot to insert the staple, a yield- 130

- ing connection between said staple carrier and driver, a lock between the staple carrier and driver, means for unlocking the driver as soon as the staple carrier brings the staple into position for driving, mechanism for making and delivering staples to said staple carrier, said mechanism comprising a staple former and loop bar, and means whereby the said loop bar is moved into the path of the staple carrier, said staple former being rigidly connected with the staple driver, whereby the staple former and staple driver move always in unison, and said loop bar having a portion engaged by the end of the staple driver to push the loop bar back into the path of the staple former.
5. In a stapling machine, a staple former and a staple driver rigidly connected together to move always in unison, and means whereby the said staple former is making one staple at the same time that the said staple driver is inserting another staple, including a movable guide for the staple, and a loop bar mounted to move in and out of the path of said guide and driver, coöperating with said former to make the staple.
6. In a stapling machine, a staple former and a staple driver rigidly connected together to move always in unison, and means whereby the said staple former is making one staple at the same time that the said staple driver is inserting another staple, the said means comprising a loop bar, means for moving the loop bar into the path of the staple driver, and means for receiving the staple and holding it in position to be inserted by said driver.
7. An inside end stapler for boxes or crates, comprising a stapling head provided with a gage for engaging the inner surfaces of the box or crate to properly position the same, and with means for both forming and driving the staples in one and the same direction, adapted to fully insert each staple while the box is stationary, said means including a staple former and a stapler driver, which move in unison, a guide for the staple, and a loop bar coöperating alternately with said former and guide.
8. An inside end stapler for boxes or crates, comprising a stapling head provided with a gage for engaging the inner surface of the box or crate to properly position the same, and with means for forming and driving the staples in the same direction, but in different planes, the forming means including a loop bar constructed and arranged to transfer the staple from one plane to the other.
9. An inside end stapler for boxes or crates, comprising a stapling head provided with a gage for engaging the inner surface of the box or crate to properly position the same, and with means for forming and driving the staples in the same direction, but in different planes, the forming means includ-
- different planes, the forming means including a loop bar constructed and arranged to transfer the staple from one plane to the other, the said direction in which the staples are both formed and driven being at an angle between the side and end of the box or crate.
10. An inside end stapler for boxes or crates, comprising a stapling head provided with a gage for engaging the inner surface of the box or crate to properly position the same, and with means for forming and driving the staples in the same direction, but in different planes, the forming means including a loop bar constructed and arranged to transfer the staple from one plane to the other, the said head being disposed at an oblique angle to the box or crate to permit the staples to be driven close to the said inner surfaces of the box or crate.
11. An inside end stapler for boxes or crates, comprising a stapling head provided with a gage for engaging the inner surfaces of the box or crate to properly position the same, and with means for forming and driving the staples in the same direction, but in different planes, the forming means including a loop bar constructed and arranged to transfer the staple from one plane to the other, said means including a rack bar, a driver actuated by said bar and rigid therewith, and a pinion for operating said rack.
12. An inside end stapler for boxes or crates, comprising a stapling head provided with a gage for engaging the inner surface of the box or crate to properly position the same, and with means for forming and driving the staples in the same direction, but in different planes, the forming means including a loop bar constructed and arranged to transfer the staple from one plane to the other, said means including a staple former and staple driver, which move in unison, a guide for the staple, said loop bar coöperating alternately with said former and guide.
13. An inside end stapler for boxes or crates, comprising a stapling head provided with a gage for engaging the inner surface of the box or crate to properly position the same, and with means for forming and driving the staples in the same direction, but in different planes, the forming means including a loop bar constructed and arranged to transfer the staple from one plane to the other, said means including devices whereby one staple is made while another staple is being driven.
14. An inside end stapler for boxes or crates, comprising a stapling head provided with a gage for engaging the inner surface of the box or crate to properly position the same, and with means for forming and driving the staples in the same direction, but in different planes, the forming means including a loop bar constructed and arranged to

- transfer the staple from one plane to the other, said means disposed in position to insert the staples with the heads thereof extending cross-wise of the cleats of the box or crate.
- 5 15. A machine for stapling the end walls to the cleats of wire bound boxes, by inserting the staples outwardly through said end walls and into the cleats, comprising means for engaging the inner surfaces of the sides of the box, to properly position the box during the stapling operation, a pivoted loop bar, a staple former coöperating with said bar to form the staples, a driver arranged for inserting the staples in the aforesaid manner, and a support in which said former and driver both reciprocate in one and the same direction.
- 10 16. A machine for stapling the end walls to the cleats of wire bound boxes, by inserting the staples outwardly through said end walls and into the cleats, comprising means for engaging the inner surfaces of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, devices for feeding wire at right angles to said direction, across the path of said former, and means for oscillating said loop bar into and out of the path of said driver.
- 15 17. A machine for stapling the end walls to the cleats of wire bound boxes, by inserting the staples outwardly through said end walls and into the cleats, comprising means for engaging the inner surfaces of the sides of the box, to properly position the box during the stapling operation, a pivoted loop bar, a staple former coöperating with said bar to form the staples, a driver arranged for inserting the staples in the aforesaid manner, and a support in which said former and driver both reciprocate in one and the same direction, said means including a stationary box support shaped for successively engaging the three side walls of the box.
- 20 18. A machine for stapling the end walls to the cleats of wire bound boxes, by inserting the staples outwardly through said end walls and into the cleats, comprising means for engaging the inner surfaces of the sides of the box, to properly position the box during the stapling operation, a pivoted loop bar, a staple former coöperating with said bar to form the staples, a driver arranged for inserting the staples in the aforesaid manner, and a support in which said former and driver both reciprocate in one and the same direction, said means including a stationary box support having its end beveled at each side thereof, and provided
- 25 between said bevels with a slot for said driver, said former being provided with means for cutting off a length of wire for each staple.
- 30 19. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, said former and driver being disposed parallel in different planes, and means for causing said loop bar to transfer the staple from the forming plane to the driving plane.
- 35 20. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, the axis of said loop bar being disposed at an angle to the plane of the end wall in position to receive the staples.
- 40 21. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, a guide for directing the insertion of the staple, and means for shifting said loop bar into and out of the path of said guide.
- 45 22. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, and means coöperating with said

driver to insert one staple while said former and loop bar are coöperating to form another staple.

23. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, said former and driver being interconnected against relative movement thereof, and a guide coöperating with said driver to insert the staple.

24. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, a clamp for engaging the cleats to resist the thrust of said driver, a shaft for operating said clamp, means for connecting said driver with said shaft, a device for feeding wire to said loop bar, and means for connecting said device with said shaft.

25. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, a support in which said former and driver both reciprocate in one and the same direction, a spring for holding said loop bar in engagement with the driver during the staple driving and forming operations, and means for engaging said former to hold said loop bar in operative position during the staple forming operation.

26. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid

manner, a support in which said former and driver both reciprocate in one and the same direction, a curved tube leading to said loop bar and former, a device for feeding wire through said tube, mechanism between said devite and former for operating said driver, and means for actuating said mechanism.

27. A machine for stapling the end walls to the cleats of wire bound boxes, by inserting the staples outwardly through said end walls and into the cleats, comprising means for engaging the inner surface of the sides of the box, to properly position the box during the stapling operation, a pivoted loop bar, a staple former coöperating with said bar to form the staples, a driver arranged for inserting the staples in the aforesaid manner, and a support in which said former and driver both reciprocate in one and the same direction, said means including a stationary box support.

28. A machine for stapling the end walls to the cleats of wire bound boxes, by inserting the staples outwardly through said end walls and into the cleats, comprising means for engaging the inner surface of the sides of the box, to properly position the box during the stapling operation, a loop bar, a staple former coöperating with said bar to form the staples, a driver arranged for inserting the staples in the aforesaid manner, and a support in which said former and driver both reciprocate in one and the same direction.

29. A machine for stapling the end walls to the cleats of wire bound boxes, by inserting the staples outwardly through said end walls and into the cleats, comprising means for engaging the inner surface of the sides of the box, to properly position the box during the stapling operation, a loop bar, a staple former coöperating with said bar to form the staples, a driver arranged for inserting the staples in the aforesaid manner, and a support in which said former and driver both reciprocate in one and the same direction, said means including a stationary box support.

30. A machine for stapling the end walls to the cleats of wire bound boxes, by inserting the staples outwardly through said end walls and into the cleats, comprising means for engaging the inner surface of the sides of the box, to properly position the box during the stapling operation, a loop bar, a staple former coöperating with said bar to form the staples, a driver arranged for inserting the staples in the aforesaid manner, and a support in which said former and driver both reciprocate in one and the same direction, said means including a stationary box support having its ends beveled at each side thereof, and provided between said bevels with a slot for said driver, said former being provided with means for 130

cutting off a length of wire for each staple.

31. A stapling machine comprising a loop bar, a staple former coöperating with said bar to form the staples, a driver arranged for inserting the staples in the desired manner, a support in which said former and driver both reciprocate in one and the same direction, said former and driver being disposed parallel in different planes, and means for causing said loop bar to transfer the staple from the forming plane to the driving plane.

32. A stapling machine comprising a loop bar, a staple former coöperating with said bar to form the staples, a driver arranged for inserting the staples in the desired manner, a support in which said former and driver both reciprocate in one and the same direction, a guide for directing the insertion of the staple, and means for shifting said loop bar into and out of the path of said guide.

33. A stapling machine comprising a movable loop bar, a staple former coöperating with said bar to form the staples, a driver arranged for inserting the staples in the desired manner, a support in which said former and driver both reciprocate in one and the same direction, and means coöperating with said driver to insert one staple while said former and loop bar are coöperating to form another staple.

34. A stapling machine comprising a movable loop bar, a staple former coöperating with said bar to form the staples, a driver arranged for inserting the staples in the desired manner, a support in which said former and driver both reciprocate in one and the same direction, said former and driver being interconnected against relative movement thereof, and a guide coöperating with said driver to insert the staple.

35. A machine for stapling the end walls to the cleats of wire bound boxes, by inserting the staples outwardly through said end walls and into the cleats, comprising means for engaging the inner surface of the sides of the box, to properly position the box during the stapling operation, a loop bar, a staple former coöperating with said bar to form the staples, a driver arranged for inserting the staples in the aforesaid manner, a support in which said former and driver both reciprocate in one and the same direction, a curved tube leading to said loop bar

and former, a device for feeding wire through said tube, mechanism between said device and former for operating said driver, and means for actuating said mechanism.

36. A stapling machine comprising a loop bar, a staple former coöperating with said bar to form the staples, a driver arranged for inserting the staples in the desired manner, a support in which said former and driver both reciprocate in one and the same direction, a spring for holding said loop bar in engagement with the driver during the staple driving and forming operations, and means for engaging said former to hold said loop bar in operative position during the staple forming operation.

37. A stapling machine comprising means for forming and driving the staples in the same direction, but in different planes, the forming means including a movable loop bar constructed and arranged to transfer the staple from one plane to the other.

38. A stapling machine comprising means for forming and driving the staples in the same direction, but in different planes, the forming means including a movable loop bar constructed and arranged to transfer the staple from one plane to the other, said means including a rack bar, a driver actuated by said bar and rigid therewith, and a pinion for operating said rack.

39. A stapling machine comprising means for forming and driving the staples in the same direction, but in different planes, the forming means including a movable loop bar constructed and arranged to transfer the staple from one plane to the other, said means including a staple former and staple driver, which move in unison, and a guide for the staple, said loop bar coöperating alternately with said former and guide.

40. A stapling machine comprising means for forming and driving the staples in the same direction, but in different planes, the forming means including a movable loop bar constructed and arranged to transfer the staple from one plane to the other, said means including devices whereby one staple is made while another staple is being driven.

Signed by me at St. Joseph, Mich., this 10th day of July, 1911.

EDWARD CRAIG.
